US00D876525S

(12) **United States Design Patent** (10) Patent No.: **US D876,525 S**
Sun et al. (45) Date of Patent: **** Feb. 25, 2020**

(54) **DEVICE OF CLEARING SENSOR
AUTOMATICALLY**

(71) Applicant: **TuSimple**, San Diego, CA (US)

(72) Inventors: **Jie Sun**, Beijing (CN); **Xiaoping Gu**, Beijing (CN)

(73) Assignee: **TuSimple, Inc.**, San Diego, CA (US)

(**) Term: **15 Years**

(21) Appl. No.: **29/657,576**

(22) Filed: **Jul. 24, 2018**

(30) **Foreign Application Priority Data**

Jan. 25, 2018 (CN) 2018 3 0036824

(57) **CLAIM**

The ornamental design for a device of clearing sensor automatically, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever. FIG. 1 is a front elevational view of a device of clearing sensor automatically showing our new design; FIG. 2 is a front plan view thereof; FIG. 3 is a bottom plan view thereof; FIG. 4 is a top plan view thereof; FIG. 5 is a right-side plan view thereof; FIG. 6 is a rear plan view thereof; and, FIG. 7 is a left-side plan view thereof.
